(57) **CLAIM**

The ornamental design for a graphic user interface for a mobile terminal, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a graphic user interface for a mobile terminal; and,

FIG. 2 is a front view of the graphic user interface for a mobile terminal of FIG. 1.

The broken line drawing of a mobile terminal is for illustrative purpose only and forms no part of the claimed design.

The AccuWeather.com trademark in the upper left portion of the Figures is a registered trademark of AccuWeather Inc. The Yahoo! or Yahoo! Finance trademark in the center left portion of the Figures is a registered trademark of Yahoo! Inc. The Associated Press or Associated Press Mobile in the center left portion of the Figures is a registered trademark or the property of a not-for-profit news cooperative, owned by its American newspaper and broadcast members. The YouTube trademark in the lower right portion of the Figures is a registered trademark or the property of Google Inc. Trademarks are the property of their respective owners.
